CASTER FOR POWDERED CONDIMENTS

Ulrich Bieger and Alexander Bieger,
Stuttgart, GermanyApplication March 29, 1934, Serial No. 718,024
In Germany December 8, 1932

7 Claims. (Cl. 65—45)

The invention relates to casters for powdered condiments, of the kind wherein the orifice of the container is normally closed by a plunger, which is moved by hand for opening the orifice. 5 The object of our invention is to enable a caster of this kind to be used for holding two condiments (say salt and pepper) simultaneously, and for this purpose we make the plunger hollow, so that it can serve as a holder for one of 10 the condiments, and we provide the plunger with a discharge orifice having a manually controlled closure. Various kinds of manually controlled closures may be used. For example there may be a second plunger, within the hollow plunger, 15 operating in the same way as the latter, or the closure may be a rotatable shutter actuated by means of a rod having a handle outside the container. In this case the arrangement may be such that the handle used for rotating the 20 shutter serves also for actuating the hollow plunger.

Examples of condiment casters constructed according to the invention are shown in the accompanying drawing.

Figs. 1 and 2 show one example, Fig. 1 being 25 a vertical section and Fig. 2 a cross-section on the line A—B of Fig. 1.

Figs. 3 and 4 are similar views of another form of construction, Fig. 4 being a section on the line C—D of Fig. 3.

30 Fig. 5 is a vertical section showing a modification of a detail of the device.

Referring first to the construction shown in Figs. 1 and 2, the container 1 has therein a plunger 2 with a tubular rod 2¹ extending upwards 35 through a cavity in the top of the container. A stud 3 projecting from the container is fixed to the rod and has a central bore. A spring 4 coiled round the rod is interposed between the lower edge of the stud and the base of the cavity 40 through which the rod passes. The container has at the bottom an opening, into which a foot 5 is screwed. The foot has a central bore, downwardly tapered, and the plunger 2 normally fits closely into the lower orifice of this bore. The 45 plunger 2 has, however, a short distance above its lower end an annular constriction 6, and when by depression of the plunger this constriction is placed within the lower orifice there is an annular passage round the plunger for discharge of the granular condiment 8, e. g. salt, 50 from the space 7 surrounding the plunger inside the container.

Within the hollow plunger 2 there is a plunger 11, the rod of which extends upwards through 55 the tubular rod 2¹ and the stud 3. At its upper

end the rod of the plunger 11 has a knob 12 fitting into the bore of the stud 3 but normally projecting from it at the top, as shown in Fig. 1, a coiled spring 13 being interposed, in the bore, between the knob 3 and the top edge of the 60 plunger rod 2¹.

The cavity 9 in the plunger 2, surrounding the plunger 11, contains a second granular condiment 10, say pepper, the discharge of which is normally prevented by a collar 14, which is 65 screwed to the lower end of the plunger 2 and into which the plunger 11 fits. The plunger 11 has, however, a short distance above its lower end a constriction 15, so that by depressing the stud 12 and plunger 11 the constricted part can 70 be pushed out of the collar 14, as indicated by broken lines in Fig. 1, thus allowing condiment 10 to be discharged.

It will be clear that the plungers can be used 75 separately, so as to obtain discharge of only one or other of the condiments. Pressure exerted in the direction of the arrow (Fig. 1) by placing a finger on the knob 3 compresses the spring 13, so that the plunger 11 is lowered within the plunger 2, leaving the latter stationary, or nearly 80 so. Pressure exerted by placing a finger on the rim of the stud 3 causes both plungers to descend, but the plunger 11 is not moved relatively to the plunger 2, so there is no discharge from the cavity 9. 85

Access to the interior of the container 1 and plunger 11, for filling the same, is obtained by unscrewing the foot 5 and collar 14.

In the construction shown in Figs. 3 and 4 the container, designated 16, has therein a hollow 90 plunger 17. From the top of this plunger, near its rim, a short rod 18 projects into a bore in the top of the container, to prevent rotation of the plunger. The cavity 19 in the container, round the plunger 17, is used for one of the condiments, say salt. At the bottom this cavity is normally closed by a cap 21 screwed to the lower end of the plunger. The cap has holes 22 therein. A rod 23 extends vertically through the plunger 95 and through a cavity in the top of the container, and has a knob 24 fixed to its upper end. A small disk 25 resting on the cap 21 is fixed to the lower part of the rod 23, and has holes 26 therein. The rod 23 extends through the cap 21, and has a nut 27 screwed to its lower end. At 100 the base of the cavity there is a fixed cam disk 29, having a ridge, and on a squared portion 23¹ of the rod within the cavity there is a cam disk 30 having a recess, whereby it is adapted to fit upon the disk 29. The disk 29 can slide on the 105 rod 23. The rod 23 is held in the cavity by a 110

squared part 3¹ of the rod, but cannot rotate thereon. A coiled spring 28 is interposed between the knob 24 and the disk 30, and is normally under slight compression, due to the rod 23 being held down by the nut 27. The pressure of the spring 28 causes the disk 30 normally to assume the position in which it fits closely upon the surface of the disk 29. By this means the rod 23 is held in such a position that the holes 26 in the disk 25 are out of register with the holes 22 in the cap 21. Consequently there can be no discharge from the space 20 within the plunger 17, but by turning the knob 24 the holes can be brought into register. On release of the knob, after turning it, the disk automatically resumes its normal position. Discharge from the space 19 round the plunger 17 is obtained by depressing the rod 23 and thus removing the cap from the opening at the bottom of the container.

20 The caster shown in Figs. 3 and 4 may be modified so that it serves also as a grinder, e. g. for peppercorns placed in the space 20. For this purpose a grinding wheel is provided, operated by rotation of the rod 23, and a grinding member coacting therewith is provided in the plunger or on the cap 21.

Fig. 5 shows a modification in which a stud and knob are used for actuating two plungers in the manner described with reference to Figs. 1 and 2. In this modification the top of the stud, designated 3¹, for actuating the external plunger is normally at the higher level, the knob 12¹ of the inner plunger being in a cup formed in the stud.

35 The caster may be made of wood, metal, synthetic resin or any other convenient material. What we claim as our invention and desire to secure by Letters Patent of the United States is:—

40 1. A condiment caster comprising in combination a condiment container having a discharge orifice, a hollow plunger in said container adapted to close said discharge orifice and having an orifice capable of discharging through said discharge orifice of said container, a closure for the orifice of said plunger, means for moving said plunger whereby said discharge orifice of said container is opened, and means for moving said closure whereby said plunger orifice is opened.

45 2. A condiment caster comprising in combination a condiment container having a discharge orifice, a hollow plunger in said container adapted to close said discharge orifice and having an orifice capable of discharging through said discharge orifice of said container, a second plunger in said first mentioned hollow plunger, adapted to close said plunger orifice, means for moving said first mentioned plunger to open said discharge orifice of said container, and means for moving said second mentioned plunger to open said plunger orifice.

50 3. A condiment caster comprising in combination a condiment container having a discharge orifice, a hollow plunger in said container adapted to close said discharge orifice and having an orifice capable of discharging through said discharge orifice of said container, a second plunger in said first mentioned hollow plunger, adapted to close said plunger orifice, a tubular plunger rod fixed to said hollow plunger extending through the wall of said container, whereby said

hollow plunger can be moved to open said discharge orifice of said container, and a plunger rod fixed to said second mentioned plunger and disposed within said hollow rod, whereby said second mentioned plunger can be moved to open said plunger orifice. 80

4. A condiment caster comprising in combination a condiment container having a discharge orifice, a hollow plunger in said container adapted to close said discharge orifice and having an orifice capable of discharging through said discharge orifice of said container, a second plunger in said first mentioned hollow plunger, adapted to close said plunger orifice, a tubular plunger rod fixed to said hollow plunger extending through the wall of said container, whereby said hollow plunger can be moved to open said discharge orifice of said container, and a plunger rod fixed to said second mentioned plunger and disposed within said hollow rod, whereby said second mentioned plunger can be moved to open said plunger orifice, said plunger rods having portions of different lengths outside said container. 85

5. A condiment caster comprising in combination a condiment container having a discharge orifice, a hollow plunger in said container adapted to close said discharge orifice and having an orifice capable of discharging through said discharge orifice of said container, a closure for the orifice of said plunger consisting of a perforated plate fixed in said orifice and a rotatable perforated plate on said fixed plate, means for moving said plunger whereby said discharge orifice of said container is opened and means for rotating said perforated plate whereby the perforations therein are placed in register with the perforations in said fixed plate. 100

6. A condiment caster comprising in combination a condiment container having a discharge orifice, a hollow plunger in said container adapted to close said discharge orifice and having an orifice capable of discharging through said discharge orifice of said container, a closure for the orifice of said plunger consisting of a perforated plate fixed in said orifice and a rotatable perforated plate on said fixed plate, a spring device whereby said rotatable plate is normally held in a position whereby its perforations are out of register with the perforations in said fixed plate, 115 means for moving said plunger whereby said discharge orifice of said container is opened, and means for rotating said perforated plate whereby the perforations therein are placed in register with the perforations in said fixed plate. 120

7. A condiment caster comprising in combination a condiment container having a discharge orifice, a hollow plunger in said container adapted to close said discharge orifice and having an orifice capable of discharging through said discharge orifice of said container, a closure for the orifice of said plunger consisting of a perforated plate fixed in said orifice and a rotatable perforated plate on said fixed plate, and means including an axially movable and rotatable member for moving said plunger to open said discharge orifice of said container and for rotating said rotatable plate to place the perforations therein in register with the perforations in said fixed plate. 135
